JAMES CAMROD LEDEBETTER, OF NEW YORK, N. Y., ASSIGNOR TO THE PROSPERITY COMPANY, INC., OF SYRACUSE, NEW YORK, A CORPORATION OF NEW YORK

GARMENT OR IRONING PRESS

Application filed July 20, 1926, Serial No. 123,612. Renewed October 16, 1928.

This invention relates to pressing machines and more particularly to steam power presses for laundry work and garment pressing work.

5 An object of the invention is to produce an improved press, for example a cuff and neck band press construction involving simple power producing mechanism by which high jaw compression on the work is attained by use of steam to operate the power or motor means.

10 A further object of the invention is to produce an improved cuff and neck band laundry ironer wherein the motor means as for example an improved disk diaphragm is incorporated with the jaw structure.

15 The accompanying drawing illustrates an example of the press construction and it is to be understood that changes in structure and operation may be resorted to without departing from the principle of the invention. The invention is merely illustrated in connection with a cuff and neck band type press, but any shape press jaw may be used.

20 25 Figure 1 shows a side view of the press in open position.

Figure 2 shows a fragmentary front view of the press with the power jaw in section as taken on the line 2-2 of Figure 1 to illustrate the heating chamber and motor means by which high jaw compression is attained.

30 35 Figure 3 is an underneath view of the power jaw removed from the frame of the machine and illustrates a bottom plan view of the disk diaphragm mounted thereunder.

40 Referring now to the drawings there is shown a stationary frame or legs 10 on the upper end of which is made a circular upper standing flange in the form of a short cylinder 11 together with an integral frame web 12 joining together the top of the frame legs. The flange 11 constitutes a cylinder wall in which a power jaw sleeve undergoes slight

45 relative high power movement. Ears 13 may be cast integral on the frame 10 if desired by which to mount and hold stationary a steam lead and steam return pipe as later referred to.

50 A vertically movable power jaw or press

buck 15 which may be of the cuff and neck band type is made with a heating chamber 16. A cylindrical sleeve 17 depends integrally from the jaw and from an integral sleeve head 14. The sleeve 17 slidably fits 55 into the cylinder 11 and works up and down therein under steam pressure as will be described. Steam lead and return pipes 18 and 19 are mounted in the frame ears 13 and the upper ends of these pipes project 60 into the jaw 15 and connect with the heating chamber 16. Stuffing box nuts 20 are screw threaded into the jaw 15 to produce a steam tight sliding fit between the pipes 18 and 19 and with the jaw, and the stuffing nuts 65 20 permit the jaw 15 to slide relatively up and down on the pipes 18 and 19 which are stationary. Through the pipes 18 and 19 steam is lead to and from the jaw heating chamber 16 to raise the temperature thereof 70 to suitable ironing heat.

A disk diaphragm 22 has its periphery anchored and sealed against a shoulder 23 by a threaded ring 28 within the sleeve 17 of the power jaw and the center of the diaphragm 75 is anchored under a washer 24 sealed in by a nut 25 thereby rigidly mounting the center of the flexible diaphragm on a stationary boss 26 integral with the frame web 12. This construction affords a closed steam chamber 27 80 defined by the sleeve 17, by the flexible diaphragm 22, and the sleeve head 14.

A steam pressure feed pipe 30 is rigidly mounted in the frame web 12 by the nut 25 aforesaid and the upper end of the pipe 30 85 therefore opens directly into the steam expansion chamber 27 above the corrugated flexible diaphragm disk 22. A discharge or exhaust valve 31 is included in the pipe 30 to permit the discharge and the exhaust of steam 90 to atmosphere from the steam expansion chamber 27. This valve may be rotated by a valve arm 32 connected with a link 33 and to a pedal 34 if desired.

A throttle or inlet steam valve 36 is also 95 included in the pipe 30 by which steam is automatically turned into the expansion chamber 27 at the time the press is closed. The throttle valve 36 is provided with a spring closed valve plunger 37 which is automatical- 100

ly depressed as later seen when the press is closed in order to permit flow of steam into the expansion chamber 27 thereby starting jaw compression.

5 A press head 39 is carried on the upper end of a swinging press lever or upright 40 which is pivoted in the frame under the press jaw at 41 and which may be integrally made with a pedal 42. By depressing the pedal 42 the press is closed, that is to say the press jaws 39 and 15 are swung into alignment. The throttle valve trip 43 is mounted on the press lever 40 in alignment with the throttle valve stem 37 so that the throttle valve 36 is opened by the trip 43 simultaneously with the closing of the press head 39.

10 A head closing handle 43 is ordinarily provided on the press lever 40 so that the press may be closed manually or by pedal 42, or 20 by both such means. After the cuff and neck band or other work is spread upon the buck 15, the head 39 is swung forwardly over the work. Sufficient clearance is permitted between the working faces of the two jaws as 25 to permit easy opening and closing motion. The inrush of steam into the expansion chamber 27, occasioned by automatically opening the throttle valve 36, causes great pressure within the expansion chamber against the 30 flexible diaphragm. Inasmuch as the jaw sleeve 17 is sealed in by the flexible diaphragm 22, the pressure of steam against the head 14 causes instant upward travel of the jaw sleeve 17 within the cylinder 11, the diaphragm 22 35 flexing at the same time.

40 Thus high jaw compression is caused against the press head 29 thereby pressing the work in the press. As long as the throttle valve 36 is held open, the compression continues. The operator by depressing the exhaust valve control pedal 34, swings the valve arm 32 to close the steam feed pipe 30 and thereby opens an exhaust pipe 46 which permits exhaust of steam from the expansion 45 chamber 27 outwardly to atmosphere. The flexibility of the diaphragm together with the weight of the jaw 15 causes the power jaw to drop downwardly thus producing clearance between the press head 39 and buck where- 50 upon the press may open. The opening movement of the lever 40 causes the throttle valve 36 to automatically close and by removal of his foot from the pedal 34, the operator causes the exhaust valve 31 to close which now opens 55 the pipe 30. A tension spring 47 pulls upwardly on the pedal 34 to continuously close the exhaust valve so that the press is in readiness for the next operation.

60 This power operated cuff and neck band press possesses the advantage of having its motor means located directly adjacent the movable jaw thereby simplifying the structure. The press uses the same steam to produce compression as is used to heat the press. 65 Inasmuch as the diaphragm 22 hermetically

seals in the expansion chamber 27, there can occur no leaking of water by reason of steam condensation because the condensate runs back through the pipe 30 and does not leak onto the floor.

70 While V-shaped press jaws are shown, it is apparent that flat-surface press jaws for laundry ironing work or for garment pressing operations may be used. Likewise it is obvious that the motor means 22 under the buck to produce high compression may be used with any type of head swinging mechanism and the upright swingable arm 40 may be displaced with any other suitable press head operating means.

75 It is to be noted that the upright 40 is pivoted at 41 below the press jaws and thus the weight of the press head is swingable back and forth over the buck 15 and over the pivot 41 and therefore no counter weight is needed to balance the head. It is significant that the upright 40 reaches forwardly at 43 to mount the head 39 and handle 43 and on its lower end reaches forwardly to form the head opening and closing pedal 42. In other words the upright-head support 40 is placed to the rear of the press jaws and bends at each end past the press jaws thus forming extensions which reach toward the front of the press, and the motor means 22 for producing high jaw compression is disposed between the two forwardly reaching extensions. This arrangement provides a compact and novel press construction.

80 What I claim is:

100 1. A pressing machine comprising, a frame, a cylinder on the frame, a press jaw, a sleeve on the press jaw slidably disposed in the cylinder of the frame, a diaphragm disk disposed between the cylinder and sleeve and sealed to one of the parts, means for applying fluid pressure on one side of the diaphragm to reciprocate the sleeve, and a press head cooperating with the press jaw.

105 2. A press comprising, a frame, an open ended cylinder made on the upper end thereof, a sleeve slidably confined in the cylinder, a press jaw carried on the upper end of the sleeve, a press head cooperating with the jaw, a diaphragm sealed inside and to the sleeve, and a fluid pressure pipe passing through the diaphragm.

110 3. A press comprising, a press head, a press buck cooperating therewith, a sleeve depending from the press buck, a shoulder formed inside the sleeve, a flat disc diaphragm sealed on the shoulder thereby forming an expansion chamber in the sleeve under the buck, a steam pipe leading through the diaphragm into the expansion chamber, and a frame supporting means in which the sleeve is guided to support the press buck.

115 4. A press comprising, a frame, a cylinder made on the upper end thereof, a sleeve slidably mounted in the cylinder, a flat disc dia-

phragm in the sleeve, a ring sealing the outer edge of the diaphragm onto the sleeve, means sealing the center of the diaphragm onto the frame, and a steam pipe passing through the means and through the diaphragm.

5. A press comprising, a cooperating head and buck, a sleeve depending from the buck, a shoulder formed inside the sleeve, a flat disk diaphragm having its outer edge sealed on the shoulder, a frame on which the sleeve and buck movably rests, and a steam pipe projecting through the center of the diaphragm.

6. A press comprising, a cooperating head and buck, a sleeve depending from the buck, a shoulder formed inside the sleeve, a flat disk diaphragm having its outer edge sealed on the shoulder, a frame, an upstanding flange made on the frame into which the sleeve is received, a frame web disposed horizontally beneath the diaphragm, a steam pipe passing through the web and diaphragm, and means sealing the pipe inside the diaphragm and anchoring the diaphragm center to the frame web.

25. 7. In a press, a frame and cooperating press jaws, operating means connected with one jaw to open and close the press, motor means connected with a jaw to produce pressure, the jaw connected with the motor means being provided with a heating chamber, a steam pipe disposed on each side of the motor means and connected with the heating chamber, and a movable joint cooperating with and included in each pipe whereby the motor actuated jaw having the heating chamber may move in relation to the frame.

8. In a press, a frame including a horizontal cross web, a buck mounted movably above the web, a fluid-pressure diaphragm attached to the cross web and to the buck including means producing a fluid-expansion chamber between the diaphragm and buck, a fluid-pressure-supply pipe extending thru the web and thru the diaphragm and being connected with the chamber, a press head mounted above the buck, and operating means connected with the head to open and close the press.

9. In a press, a frame including a horizontal cross web, a buck mounted movably above the web, a fluid-pressure diaphragm attached to the cross web and to the buck including means producing a fluid-expansion chamber between the diaphragm and buck, a fluid-pressure-supply pipe extending thru the web and thru the diaphragm and being connected with the chamber, a throttle valve mounted in the pipe and means holding said valve closed, a press head mounted above the buck, an upright pivoted under the jaws and attached to the head to open and close the press, and said upright being adapted to engage and automatically open the throttle valve when the press closes.

10. In a press, a frame and a cooperating press head and buck both of which are mov-

able in relation to the frame and to each other, a flat-type-disc diaphragm having concentric corrugations and having its center engaging the frame, a steam supply pipe passed through the frame and sealed into the center of the diaphragm, the periphery of the diaphragm engaging the buck, a sealing ring affixed to the periphery of the diaphragm and buck, and operating means to swing the head to open and close the press.

In testimony whereof I affix my signature.
